CLAIM

The ornamental design for a substrate for spectroscopic analysis, as shown and described.

DESCRIPTION

1. Substrate for spectroscopic analysis

1.1 : Perspective

1.2 : Front

1.3 : Back

1.4 : Top

1.5 : Bottom

1.6 : Left

1.7 : Right

1.8 : SECTIONAL VIEW

1.9 : SECTIONAL VIEW

1.10 : PERSPECTIVE VIEW WITHOUT THE COVER PART

The broken line showing the substrate for spectroscopic analysis is for the purpose of illustrating environmental structure and forms no part of the claimed design.

The dot-dash broken lines define the bounds of the claimed design and form no part thereof.
